PATENTED MAY 15, 1906.

F. A. MILLS.
SHUTTLE CHECKING MEANS FOR LOOMS.
APPLICATION FILED JULY 16, 1904.

UNITED STATES PATENT OFFICE.

FRANCIS ARTHUR MILLS, OF LAWRENCE, MASSACHUSETTS, ASSIGNOR
OF ONE-HALF TO GROSVENOR B. EMMONS, OF METHUEN, MASSA-
CHUSETTS.

SHUTTLE-CHECKING MEANS FOR LOOMS.

No. 820,663.

Specification of Letters Patent.

Patented May 15, 1906.

Application filed July 16, 1904. Serial No. 216,851.

To all whom it may concern:

Be it known that I, FRANCIS ARTHUR MILLS, a citizen of the United States, residing at the city of Lawrence, in the county of Essex and State of Massachusetts, have invented certain new and useful Improvements in Shuttle-Checking Means for Looms; and I do hereby declare the following to be a full, clear, and exact description of the invention, such as will enable others skilled in the art to which it appertains to make and use the same.

The following description, read in connection with the accompanying drawings, will enable any one skilled in shuttle checking and locking mechanism for looms to understand my invention and to practice it in the form in which I prefer to employ it; but it will be understood that my invention is not limited to the precise form and details of construction herein illustrated and described, as various modifications and changes may be made without exceeding the scope of my invention and the claims.

Referring to the drawings, Figure 1 shows in top view the left shuttle-box of the lay, having the binder located at the back thereof and the shuttle in position having just come in contact with my pneumatic binder. Fig. 2 shows a like view, the shuttle having fully entered the shuttle-box and in contact with the picker and picker-stick to actuate an impact-strap to force the binder against the shuttle to check and lock it. Fig. 3 shows a side view of the same. Fig. 4 is a longitudinal section of the binder, taken on the line 4-4 of Fig. 5, showing my novel pneumatic and corrugated cushion-shuttle binder. Fig. 5 is a cross-section of the same on the line 5-5 of Fig. 4, showing the air-chambers. Fig. 6 shows the front side of the left end of the box and means for adjusting the impact-strap to cause the shuttle to be stopped and locked at a predetermined position in the shuttle-box. Fig. 7 shows the protection-finger arranged to operate the binder between the latter and the impact-strap. Fig. 8 shows the same in top view.

The object of my present invention is to arrange an impact-strap so as to yieldingly force a shuttle-binder against the shuttle. To cause this operation, I provide a novel ar-

rangement and connection of the impact-strap with the shuttle-box or lay so as to co-operate with the shuttle-binder to cause the latter to be yieldingly pressed upon the shuttle by the impact of the shuttle upon the picker.

The lay 1, the shuttle-box 2 thereon, the shuttle 3, and picking mechanism therefor may be of the usual form and construction. My invention resides in checking and locking the shuttle at a predetermined position within the shuttle-box, and the means for effecting this I will now describe.

An impact-strap 4 is arranged at the back of the binder 7 and has one end 5 connected to the lay or shuttle-box, passing across a movable part 6 of a binder 7 around the picker 8 and picker-stick 9 and fastened to an adjustable means which is connected to the box or lay, so that the impact of the shuttle upon the picker or picker-stick will cause impact upon the strap to cause it to force the binder against the shuttle.

While I have shown the impact-strap as crossing the path of the picker-stick above the lay, obviously that part of the strap which receives the impact of the picker or picker-stick caused by the shuttle may be dropped beneath the lay around the picker-stick and adjustably connected to the lay.

The binder is pivoted to the lay and forms one side of the shuttle-box and is constructed as follows: The contact-face of the binder 85 may be of leather or a thin sheet of metal 10, fastened upon the binder, and the binder is preferably made in sections and riveted together at its fulcrumed end. Between said contact-facing and the binder is seen a pneumatic cushion 11 to coact with the shuttle. This pneumatic cushioned shuttle-binder, as seen in the drawings, produces its pneumatic function upon the shuttle by one or more air-chambers 12, preferably parallel with the binder, so as to produce a pneumatic function upon the shuttle when the latter strikes it and when the said binder is forced against the shuttle by the impact-strap. Coacting with the pneumatic chamber or chambers the face of the pneumatic cushion which joins the binder has corrugations 13 to increase the cushion or pneumatic effect when the shuttle strikes the binder and when the binder is

forced against the shuttle by the effect of the impact of the shuttle upon the picker or picker-stick upon said strap.

Referring to the impact-strap, the means for adjusting it to provide for the stretch of the strap and wear of the picker by the impact of the shuttle, so as to stop the shuttle at a predetermined position in the shuttle-box, are seen in Figs. 1, 2, and 6, and consists of a revoluble stud or post 14, secured by a clamp-nut to a bracket 15, which is bolted to the lay, and to said post the strap is fastened and wound around it, so that by loosening said nut on the stud or post the latter may be turned to wind up or let out the strap for its adjustment. I also provide means for laterally adjusting the fulcrumed end of the binder, and for this purpose the binder-fulcrum 16 is an eccentric, and by loosening a nut 17 and turning the eccentric the binder may be moved farther in or out from the opposite side of the shuttle-box. This adjustment of the shuttle-binder at its fulcrumed end is to give more or less lifting action to the protection mechanism and pneumatic pressure upon the shuttle.

Looking at Fig. 1 it will be seen that the shuttle has struck the swell of the pneumatic binder with a cushion effect, thus giving easy entrance to the box. The shuttle having entered fully in the box, as seen in Fig. 2, it will be noticed the pneumatic binder has been compressed, which also compresses the corrugated surface of said binder, caused by the impact of the shuttle upon the picker, and thereby cause a pulling action of the impact-strap which has forced said binder against the shuttle with a pneumatic locking function upon the shuttle to lock it at the desired position in the shuttle-box.

The protection device is of the usual form, having the protection-finger 18, its shaft 19, and spring 20 for forcing the finger against the binder, and looking at Figs. 1, 2, and 3 it will be seen that the protection-finger is in engagement with and pressing upon the impact shuttle-locking strap, said strap or band being shown located between the protection-finger and the movable end of the binder, so that when the shuttle strikes the pneumatic binder, forcing its free end out, will cause said strap to be frictionally drawn under spring-pressure between said binder and the protection-finger, thereby aiding in checking the shuttle while traveling in the box. The protection-finger, however, may be located between the shuttle-locking impact-strap and the binder, as seen in Figs. 7 and 8, which will cause said strap to force the protection-finger against the shuttle-binder and said binder against the shuttle to lock it.

Looking at Fig. 4 it will be understood that the impact-facing of the binder will have in its contact with the shuttle a yielding function due to the elasticity of the rubber and a

yielding function due to its pneumatic function, the combined effect of both these yielding elements being to cause the binder to conform to the shape of the shuttle while traveling and at the limit of its travel in the shuttle-box.

I claim—

1. In a loom, the lay, the shuttle-box, the shuttle-binder, the shuttle, and picking mechanism therefor, an impact-strap connected at one end to said box or lay, passing over a movable part of the binder, crossing the path of the picker or picker-stick and connected at its other end to the said box or lay.

2. In a loom, the lay, the shuttle-box, the shuttle-binder, the shuttle and picking mechanism therefor, an impact-strap connected at one end to the box or lay, passing over a movable part of the binder, crossing the path of the picker or picker-stick and connected at its other end to said box or lay, and means for adjusting said strap.

3. In a loom, the lay, the shuttle-box, the shuttle-binder, the shuttle and picking mechanism therefor, an impact-strap connected at one end to the box or lay, passing over a movable part of the binder, crossing the path of the picker or picker-stick and connected at its other end to said box or lay, and means for adjusting said strap, consisting of a revoluble stud or post to which the strap is fastened and around which the strap is wound and a nut clamping said post to a bracket bolted on the lay.

4. In a loom, the lay, the shuttle-box, a binder pivoted at or near the outer end of the lay, the shuttle and picking mechanism therefor, an impact-strap having unyielding connections at both ends with the lay and acting on the free end of said binder for the purpose stated.

5. In a loom, the lay, the shuttle-box, the shuttle and picking mechanism therefor, and pneumatic checking and locking means to act upon and conform to the shape of the shuttle when boxed.

6. In a loom, the lay, the shuttle-box, the shuttle and picking mechanism therefor, and a pivoted binder having a rubber-facing chambered to provide a pneumatic function upon the shuttle.

7. In a loom, the lay, the shuttle-box, the shuttle and picking mechanism therefor, and a shuttle-binder having a rubber body chambered to provide a pneumatic function upon the shuttle and having a corrugated seating upon the binder.

8. In a loom, the lay, the shuttle-box, the shuttle and picking mechanism therefor, and a pivoted binder having a rubber body, a wear-facing therefor, the seating-face of said rubber body corrugated and air-chambers between the corrugated seating and the wear-facing.

9. In a loom, the lay, the shuttle-box, the

shuttle and picking mechanism therefor, a rubber body, a wear-facing therefor, the seating-face of said rubber body corrugated.

10. In a loom, the lay, the shuttle-box, the shuttle and picking mechanism therefor, a pneumatic shuttle-binder and an impact-strap having connections to force said binder against said shuttle.

11. In a loom, the lay, the shuttle-box, the shuttle and picking mechanism therefor, a shuttle-binder pivoted at or near the outer end of the lay, an impact-strap connected at one end to said lay or box and passing over a movable part of said binder and crossing the path of the picker or picker-stick and connected at its other end to said lay or box and means for adjusting said strap.

12. In a loom, the lay, the shuttle-box, the shuttle and picking mechanism therefor, a pneumatic shuttle-binder and an impact-strap having connections to force said binder against said shuttle and means for adjusting said strap.

13. In a loom, the lay, the shuttle-box having a shuttle-binder, the shuttle and picking mechanism therefor, a revolvable post adjustably fixed to said lay or box, an impact-strap fastened at one end to said post and crossing the path of the picker or picker-stick and passing along the back of and crossing the free or movable end of said binder and fastened to said box or lay.

14. In a loom, the lay, the shuttle-box having a shuttle-binder, protection mechanism having a protection-finger operated by said binder, the shuttle and picking mechanism therefor, an impact-strap fastened to said lay or box crossing the back of said protection-finger and passing to and around the picker or picker-stick and adjustably connected to said lay or box, whereby the impact of the shuttle will cause said strap to force said protection-finger against said binder and said binder against the shuttle to check and lock the shuttle in the shuttle-box in a predetermined position.

15. In a loom, the lay, the shuttle-box the shuttle and picking mechanism therefor, said shuttle-box having laterally-movable pneumatic means to cause pneumatic resistance upon the ingoing shuttle to check it.

16. In a loom, the lay, the shuttle-box, the shuttle and picking mechanism therefor, and means for pneumatically checking said shut-

tle while traveling in said box including means for locking said shuttle at the end of its travel in said box under a pneumatic pressure.

17. In a loom, the lay, the shuttle-box, the shuttle and picking mechanism therefor, said shuttle-box having pneumatic means to act upon the side of the ingoing and outgoing shuttle.

18. In a loom, the lay, the shuttle-box, the shuttle and picking mechanism therefor, a shuttle-binder pivoted at or near the outer end of the lay, an impact-strap acting upon the free end of said binder and crossing around the picker or picker-stick and adjustably connected at or near the outer end of the lay or box, the other end of said strap connected to the lay or box at or near the inner free end of said binder.

19. In a loom, the lay, the shuttle-box having a shuttle-binder, protection mechanism operated by a protection-finger pressing on a movable part of said binder, the shuttle and picking mechanism therefor, an impact-strap having one end fastened to said lay or box and passing across the back of said protection-finger and across the path of the picker or picker-stick and adjustably secured at its other end to said lay or box.

20. In a loom, the lay, the shuttle-box having a shuttle-binder pivoted at or near the outer end of the lay, the shuttle and picking mechanism therefor, an impact-strap acting directly on the free end of said binder and crossing the path of the picker or picker-stick and having connections with said lay or box to cause said binder to be forced against the shuttle by the impact of the shuttle.

21. In a loom, a lay, a shuttle-box having a shuttle-binder, a protection mechanism having a protection-finger operated by said binder, a shuttle and picking mechanism therefor, an impact-strap fastened to said lay or box passing over said finger and connected to receive the impact of the picker or picker-stick caused by the impact of the shuttle.

In testimony whereof I have signed my name to this specification in the presence of two subscribing witnesses.

FRANCIS ARTHUR MILLS.
